UNITED STATES PATENT OFFICE

99,815

DESIGN FOR A COAT

Julius Leiterman, New York, N. Y.

Application March 7, 1936, Serial No. 61,514

Term of patent 3½ years

To all whom it may concern:

Be it known that I, Julius Leiterman, a citizen of the United States of America, residing in Manhattan, county of New York, and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the combination on a raglan type coat of slot seams at the upper rear portion of the garment which seams terminate at the tab on the back of the stand-up collar and fly seams on the cuff portion of the sleeves, as shown.

I claim:

The ornamental design for a coat, substantially as shown and described.

JULIUS LEITERMAN.
